STOKER FURNACE

John H. Lawrence, Bronxville, N. Y., assignor to
 Metropolitan Engineering Company, Brooklyn,
 N. Y., a corporation of New York

Application March 24, 1936, Serial No. 70,586

9 Claims.

(Cl. 122—4)

The invention provides an improvement in stoker fired furnaces adapted for a variety of uses and particularly for large steam generating boilers using high furnace temperatures. The 5 grate is water cooled for protection of the grate and of the stoker mechanism, as hereinafter described in detail.

The accompanying drawings illustrate embodiments of the invention.

Fig. 1 is a longitudinal section of a stoker fired boiler. Fig. 2 is a perspective sectional view of the grate and adjacent parts. Fig. 2a is a vertical cross section through the fuel feeding and air feeding parts of the grate, taken on the line 2a of Fig. 2. Fig. 3 is a section through one of the air feeding channels. Figs. 4, 5, 6 and 7 are side elevations illustrating alternative designs of tubes forming parts of the air feed sections. Fig. 8 is a plan of the tube shown in Fig. 7. Figs. 9, 10 and 11 are views similar to Fig. 3, showing alternative constructions of the air feed sections.

In Fig. 1 the upper part of the boiler carries a lower bank of tubes 1 and an upper bank 2 with baffles 3 and 4 by which the hot gases are directed over the tubes and finally out by the smoke outlet 5. The tubes at opposite ends run into headers 6, 7, 8 and 9; the headers on the lower ends being fed by water coming down from the drum 10. This upper structure is carried in a casing 11, 12. Numerous other arrangements of water tubes and smoke passages are known and may be utilized with this invention.

The combustion chamber of the furnace 13 is enclosed within walls 14, 15 which in the case illustrated are lined with upright tubes 16 and 17 which may be connected into the main or accessory circulation of the boiler in various known ways.

In the lower part of the furnace is the grate to which coal is fed from a hopper 18 at the front, the grate being inclined downward toward the back to an ash discharge chute 19 and disposed of in any usual way. An air chamber 20 feeds air through dampers 21 to the space beneath the grate; the air being heated generally to a high temperature in advance so as to secure the more intense combustion.

The grate is composed of longitudinal plates 22 which divide the entire area into sections or retorts. In the alternative spaces between these side plates, there are located the coal feeding sections, such as are illustrated at the front of Fig. 2, and the air feeding sections, illustrated in Figs. 3, 9, 10 and 11; the coal feeding sections alter-

nating with the air feed sections, as shown in Fig. 2a.

Referring to Fig. 2 there are fixed plates 23 extending across from one longitudinal plate 22 to the next; the plates 23 being spaced apart 5 along the length of the grate. In the intervals between the fixed plates 23 are the longitudinally reciprocable plates 24 which are attached by rocker arms 25 to rods 26 each of which is connected by a link 27 to a rod 28 running through a 10 stuffing box 29 in the front wall and connected at its outer end by a link 30 to a rocking plate 31.

At the lower end of the grate is a special plate or section 32 which is similarly connected by a rocker arm 33, link 34, rod 35 and link 36 to the 15 rocker 31 at the front. The rocker 31 at its upper end engages a plunger 37 and reciprocates the same to push down on to the grate coal which drops from the hopper 18. The inner reciprocable members 24 and 32 advance the coal to the 20 lower end of the grate as it burns, and finally dump the ash into the passage at the bottom.

The alternative spaces between the plates 22 take the hot air from below and pass it into the bed of fuel through a special cooling structure. 25 As illustrated, the closed sections of the grate are comparatively narrow so that the air will be sufficiently distributed by its passage through the alternative cooled spaces; but supplementary air passages may be provided through the sections 30 carrying the plates 23 and 24.

In this case the air channels between the plates 22 are overlain each by a tube 40 with longitudinal fins applied in the form of numerous comparatively small segments with spaces between 35 them for passage of the air.

In Fig. 3 a single tube 40, such as an ordinary three-inch or four-inch seamless steel boiler tube, for example, may be provided with projections 41 extending outward from diametrically opposite 40 points, and resting on the walls 22 of the air retort. Each of the projections is separately welded to the tube so as to ensure a good heat-conducting contact and they are spaced apart sufficiently to avoid interference with each other; 45 and close enough to secure an extensive area and an intimate air-contact.

By the separate application of the projections we secure a structure similar to a continuous fin with openings through it, but with the advantage 50 that the tubes and fins are not subjected to any excessive strains under heat of the welding operation. The rigid union of the fins to their tube not only permits them to support the tube in correct position but also maintains a good heat con- 55

ducting connection notwithstanding any warping of the parts in the operation of the furnace. Water circulates through the tubes and prevents the overheating and undue softening of the projections. It also protects the adjacent parts of the grate from overheating while permitting an extremely high temperature in the combustion air fed to the furnace and a high rate of combustion. It also tends to prevent or diminish the accumulation of fused ash on the coal feeding sections of the grate. Such an accumulation, in previous designs, has required an increasing of power for driving the stoker and has even partly cut off the flow of air through the grate at times.

15 According to Fig. 1 the water tubes 40 on the grate are continuations of some of the tubes 16 which extend down the inner face of the front wall 14 of the furnace. However, these tubes 40 may be fed from a separate header 42, as shown 20 in Fig. 2, located on the outside of the front wall just above the coal hopper 18.

The tubes 40 after passing beyond the lower end of the grate pass down as at 43, Fig. 1, along the wall of the ash pit or passage-way 19 so as to 25 provide a cooled water wall therefor. The projections 41 are not necessary in this part of the tubular structure.

Various connections for providing and taking away the water from the tubes may be arranged. 30 According to Fig. 1 there is a header 44 connected to the lower ends of all the tubes 43. Some of these tubes turn back at the end of the grate, as indicated at 44, and lead to a header 45; the other tubes leading up to connect with the tubes 35 16, previously referred to.

According to Fig. 2 the lower ends of the tube sections 43 run out of a bottom header 46 and run at their upper ends into a header 42. Generally the heat thus applied to the water is utilized by connecting the headers into the desired part of the boiler circulation, whether for steam generation or for superheating of the steam or preheating of the water.

The projections 41, previously referred to, are 45 rectangular in end view and with a greater depth than width and with their adjacent faces in planes squarely at right angles to the axis of the tube. However, they may be arranged as at 47, Fig. 5, with their adjacent faces set obliquely to 50 the axis of the tube. In that case the air is forced with a somewhat greater pressure against the faces of the projections so as to secure a better cooling effect.

In Fig. 6 there are shown projections 48 which 55 are also oblique and, in fact, have their wider faces nearly parallel with the direction of the axis.

In Figs. 7 and 8 similar projections 49 are illustrated but having their inner portions 50 of reduced width to ease the passage of the air and to provide shorter ends for welding to the tube.

There are many possible variants of the tubular unit with lateral projections shown in Fig. 3. The tube itself may be of multiple form, that is with 60 more than one passage for the water. The projections may be of various forms besides those illustrated. And the projections instead of being diametrically opposite may be applied tangentially to the tube as in Figs. 9, 10 and 11.

70 According to Fig. 9 the projections (which in cross-section may be of any of the shapes previously referred to) are formed of a single bar 51 welded at its center to the tube 48 and extending over the side plates 22 of the retort.

75 Fig. 10 illustrates a similar construction, differ-

ing only in that the projections 52 are arched for stiffness. In both Figs. 9 and 10 the tube is below so as to receive the first blast of hot air; and the portions of the bar which overlie the tube, in effect thicken the wall of the tube at the top where 5 it is most liable to be burned out and abraded by the hot traveling fuel bed. In Fig. 11 the projections 53 are in the form of a single bar welded tangentially to the tube 48 but this tubular unit is supported on the side plates 22 with the tube 10 above the projections and, therefore, closer to the bed of burning fuel and farther along in the path of the hot air.

The tubular units of Figs. 9, 10 and 11 may be 15 used in various other locations in which it is desirable to provide additional metal overlying the tube on one side which would generally be the side exposed to a much higher degree of heat than the opposite side, so as to protect the tube against overheating and burning on this exposed side and 20 also to moderate the cooling effect on the fire side of the tube, or of that portion of the length of the tube which is closest to the fire. Such tubular units of general application are covered separately in a divisional case, No. 119,539, filed 25 January 8, 1937.

In the particular case illustrated, where the tube is used as part of the grate, it is exposed to these extreme conditions along its whole length and consequently the metallic projections or extensions are to be provided along the whole length as illustrated in Fig. 1. In other locations this might not be necessary.

What I claim is—

1. A furnace having a floor for a bed of fuel 35 with air channels along said floor, parts of the floor comprising tubes for circulating a cooling medium, said tubes having longitudinal fins united thereto and overlying said air channels, said fins being in the form of numerous small 40 segments welded separately to the tube with spaces between them for the passage of air to the fuel bed.

2. A furnace having a floor for a bed of fuel with air channels along said floor, parts of the 45 floor comprising tubes for circulating a cooling medium, said tubes having longitudinal fins united thereto and overlying said air channels, said fins being in the form of numerous small segments welded separately to the tube with spaces 50 between them for the passage of air to the fuel bed, said segments over-lapping one another horizontally.

3. A furnace having a floor for a bed of fuel, with air channels along said floor, parts of the 55 floor comprising tubular units each consisting of a tube for circulating a cooling medium and having oppositely extending fins united rigidly and permanently thereto with a good heat-conducting joint thereto, each such unit spanning one of 60 the air channels and the fins having numerous closely spaced openings for the passage of air to the fuel bed.

4. A furnace having a stoker comprising a number of parallel reciprocating sections for advancing the coal, between which are tuyères for feeding the air for combustion, said tuyères each comprising side walls and a tubular unit supported thereon comprising a tube for circulating a cooling medium and fins united rigidly 70 and permanently thereto with a good heat-conducting joint to the tube and having openings through which air passes against the tubes to the fuel bed.

5. A stoker comprising a number of parallel re- 75

ciprocating sections for advancing the coal between which are tuyères for feeding the air for combustion, said tuyères each comprising side walls and a tubular unit supported thereon comprising a tube for circulating a cooling medium and fins in the form of numerous small segments welded separately to the tube and having transverse openings between them through which air passes to the fuel bed.

6. A tuyère for stokers comprising side walls and a top comprising a tubular unit, said unit comprising a tube for circulating a cooling medium and fins in the form of numerous small segments welded separately thereto and having transverse openings between them through which air can pass to the fuel bed.

7. A furnace having a floor for a bed of fuel with air channels along said floor, parts of the floor comprising tubes for circulating a cooling medium said tubes having longitudinal fins united rigidly and permanently thereto with a good heat conducting joint and overlying said air channels with numerous closely spaced transverse openings through each of said fins adapted to cause

the passage of air against the tubes and through said openings to the fuel bed.

8. A furnace having a floor for a bed of fuel with air channels along said floor, parts of the floor comprising tubes for circulating a cooling medium said tubes having longitudinal fins united rigidly and permanently thereto with a good heat conducting joint and overlying said air channels with numerous closely spaced transverse openings through each of said fins adapted to cause the passage of air against the tubes and through said openings to the fuel bed and said fins overlying said tubes so as to thicken their walls at the top.

9. A furnace having a floor for a bed of fuel with air channels along said floor, parts of the floor comprising tubes for circulating a cooling medium, said tubes having longitudinal fins united thereto and overlying said air channels with numerous closely spaced openings through said fins for the passage of air to the fuel bed, said finned tubes being supported with freedom of movement relatively to the walls of said air channels.

JOHN H. LAWRENCE.
